US0D1030422S

(12) United States Design Patent (10) Patent No.: US D1,030,422 S
(45) Date of Patent: * Jun. 11, 2024

(54) FORK

(71) Applicant: Moherlie Kristina Coles, Morningside, MD (US)

(72) Inventor: Moherlie Kristina Coles, Morningside, MD (US)

() Term: 15 Years

(21) Appl. No.: 29/825,104

(22) Filed: Jan. 28, 2022

(51) LOC (14) Cl. 07-03

(52) U.S. Cl.

USPC D7/653

(58) Field of Classification Search

USPC D7/698, 653-654, 631-635, 660, 362,
